ABSTRACT

A capsule case slitting device receives an embedded electron microscopy tissue capsule and forces the capsule with its case between oppositely spaced blades to impart longitudinal slits in the capsule case thereby enabling the embedded tissue specimen to be easily separated from its casing.

APPARATUS FOR SLITTING AN ELECTRON
MICROSCOPY TISSUE EMBEDDING CAPSULE
CASING

BACKGROUND OF THE INVENTION

1. Field of the Invention

The invention relates broadly to devices for removing molded items from their mold and specifically to devices adapted to effect the removal of an embedded electron microscopy tissue specimen from a surrounding plastic casing mold by slitting the wall of the casing.

2. Description of the Prior Art

In the art of electron microscopy minute samples of tissue which are to be examined must first be processed in various dehydrants, stains and fixatives, then embedded in a plastic material, then thinly cut into sheets on a rotary ultramicrotome, and finally placed in a grid slot for viewing under an electron microscope. A convenient means for embedding the processed tissue has been the so-called "Beem" capsule which comprises a frusto-conically shaped polyethylene casing measuring about 1.5×3.0 cm. at its larger end, and having an opening in the larger end to permit the insertion of the tissue to be examined and a fluid plastic embedding material which hardens under appropriate conditions. Before the fluid plastic has hardened, the tissue particle is required to settle to the bottom narrow tip portion of the capsule. Once hardened, it is necessary to remove the embedded plastic block from its casing preparatory to cutting the tissue on an ultramicrotome. Heretofore, a common practice for removing the block from the casing has been for a technician to hold the capsule in his hand and make several longitudinal slits in the capsule casing with a razor blade, surgical knife or the like. The wall of the casing is divided at the slits and the plastic tissue containing block is then removed. Typically, large numbers of such capsules are processed daily in an active histology laboratory and since the capsules are small and relatively difficult to grip, they tend to slip from time to time, often causing the blade to be diverted into the holder's fingers. Thus, this method is both time consuming and hazardous.

An alternate means for enabling a tissue embedding to be removed from an embedding capsule is the well-known "Beem" capsule press. This device comprises a movable arm situated above a platform having a circular aperture with a diameter corresponding to the embedded block diameter which is the same as the inside diameter of the Beem capsule casing. An embedded capsule is placed open end down on the platform and above the aperture, and the arm is forced down upon the small tip of the capsule. The embedded plastic block, being of smaller diameter than the inside diameter of the capsule casing, is squeezed through the aperture, while the capsule casing is retained above. While this apparatus and technique are successful in removing the block from the capsule casing, it is readily apparent that harm to the tissue specimen situated in the tip of the capsule may occur due to the impact and compression of the arm being forced down upon the narrow tip. The resultant compression of the tissue specimen might therefore ruin many hours work and cause irreplaceable loss in cases wherein like tissue specimens are no longer available.

In this respect, the prior art has not taught an adequate device for removal of the embedded plastic tissue block from the capsule casing without causing possible

damage to the tissue specimen, and without the likelihood that laboratory personnel might be injured in the process. When many samples must be taken and processed as is common in present hospital facilities, an efficient yet safe method and apparatus for effecting removal of the tissue blocks from the embedding capsule casings is clearly needed.

Solutions to the above problems constitute objects of the present invention. As will be perceived, other objects and advantages will appear in the description and appended claims which follow.

SUMMARY OF THE INVENTION

The apparatus of the invention comprises a base plate which can be mounted on a laboratory worktable, desk or the like. The base plate supports a guide member, a push rod assembly and a camming assembly. The guide member has a cylindrical receptacle into which a filled "Beem" type capsule is dropped. The push rod assembly includes a push rod which is designed to engage the open or filling end of the capsule and force the capsule past a pair of fixed razor blades which slit both sides of the capsule casing. The camming assembly includes a handle and a cam arranged so that when the handle is turned the cam forces the push rod against the capsule to effect slitting of the capsule casing.

DESCRIPTION OF THE DRAWINGS

FIG. 1 is a perspective view of an apparatus constructed according to the invention.

FIG. 2 is a side view of the invention apparatus showing the push rod lever and bearing assembly.

FIG. 3 is a top plan view of the invention apparatus showing the capsule aperture.

FIG. 4 is a partial cutaway top view of the invention apparatus showing the push rod in the closed position.

FIG. 5 shows the sequence in two positions of a "Beem" type embedding capsule prior to and after slitting.

FIG. 6 is a perspective view of a typical single edge, rectangular shaped razor blade suited to the invention.

DESCRIPTION OF THE PREFERRED EMBODIMENT

Referring to FIG. 1, the apparatus of the preferred embodiment generally designated 10, comprises a base member 15, vertical support members 16, 17, slitter assembly 20 and camming assembly 30. Slitter assembly 20, best shown in FIG. 4, includes guide member 21 having a central elongated cylindrical cavity 23 extending the length of guide member 21, a pair of laterally disposed elongated cylindrical cavities 24, 25 each having an open end and extending only part way the length of guide member 21, push rod mechanism 26 and blades 27, 28. Referring now to FIG. 3, guide member 21 includes a rearward portion 12 and a forward tapering portion 14, tapering to a blunt end 13. An elongated opening 11, having a beveled top peripheral edge 18, is centrally disposed in tapering portion 14 and opens into central cylindrical cavity 23 from above. Referring to FIG. 2 horizontal slots 19 formed along the opposite tapered edges of tapering portion 14 are adapted to permit insertion of suitable single edge type razor blades 27, 28, FIG. 6, so as to allow a corner end portion of each blade to extend into the mentioned central elongated cavity 23. Appropriate set screws 35, 36, 37, 38, 39 and 40, shown in FIG. 1, are adapted to

adjustably secure blades 27, 28 within slots 19. A feature of note is that blades 27, 28 are recessed in slots 19 so as to render them inaccessible to the user during normal operation thus eliminating the danger of accidental bodily injury.

Referring now to FIG. 4, push rod mechanism 26 comprises a plate member 55 to which are integrally secured a central push rod 50 and a pair of laterally spaced guide rods 41, 42 having a slightly smaller diameter than push rod 50. Rods 41, 42 are secured in an abutting relation and are rigidly secured to plate member 55 and each receives a coil spring 45. Push rod 50 extends through plate member 55 to which it is rigidly secured and has a slotted end 51 which receives pin 52 and roller 53. Rods 50, 41 and 42 are positioned in alignment with and axially movable within the respective cylindrical cavities 23, 24, 25. Springs 45 are adapted to reside within the respective cylindrical cavities 24, 25 and to surround rods 41, 42. Spring 45 thus causes the push rod mechanism 26 to assume a normally "open" position, shown in FIGS. 1, 2 and 3, until mechanism 26 is moved inwardly into guide member 20 and springs 45 compressed, as shown in FIG. 4. Upon release, springs 45 then urge mechanism 26 back into the open position.

Camming assembly 30, best shown in FIGS. 2 and 3, comprises a cam 31 secured to shaft 32 which is journaled for rotation through journal openings (not shown) in wall portions 47, 48 of support member 17. An end cap 49 is secured to an end of shaft 32 and supports a handle 46. Rotation of handle 46 causes rotation of shaft 32 and handle 46 is rotatable through an arc of approximately 180°. A peripheral track 44 in cam 31 mates with roller 53 and maintains alignment between push rod assembly 26 and cam 31 as cam 31 is manually rotated through the mentioned arc. Due to the compressive force outwardly exerted on plate 55 by springs 45, roller 53 is always held against track 44. Thus, push rod assembly 26 advances into and withdraws from guide member 20 according to the rotation of cam 31. As illustrated in FIG. 3, push rod assembly 26 is shown in an "open" position and cam 31 is shown rotated to an extreme outward position. In FIG. 4, push rod assembly 26 is shown in a "closed" position and cam 31 is shown rotated to an extreme inward position.

Referring now to FIG. 5, there is shown at position A a so-called "Beem" capsule. This type of capsule comprises a frusto-conically shaped polyethylene thin walled shell or casing 70 which acts as a mold during embedding. Casing 70 is adapted to receive an electron microscopy tissue particle and a liquid polymer embedding medium which polymerizes around the sample when subjected to appropriate environmental conditions, preparatory to being thinly sliced on a rotary ultramicrotome. Referring to FIG. 3, in order to separate the polymerized embedding material from the polyethylene capsule casing 70, the filled capsule is placed small end first into aperture 11 of the invention apparatus 10, an operation analogous to loading a cartridge into the open chamber of a bolt action rifle. As shown in FIG. 4, push rod 50 includes a blunt tip portion 68 which is slightly narrower than the inside diameter of casing 70 and which is adapted to abut against only the embedding or plastic block portion 71 of the capsule. When handle 46 rotates cam 31 in a forward direction, push rod assembly 26 is advanced into guide member 20 and blunt tip 68 abuts with the now polymerized em-

bedding portion or block 71 and urges the capsule casing 70 forward in the central cylindrical cavity 23 and between the laterally disposed blades 27, 28 so as to impart longitudinal slits 75 along both sides of the capsule casing 70. Due to the leverage afforded by the disposition of the large cam 31 with reference to roller 53 slitting of a typical capsule is now easily accomplished. FIG. 5 at position B, shows the capsule casing 70 after having been slit longitudinally and manually parted 10 along slits 75 to expose the polymerized block 70 and enables easy removal of the same.

An important feature to note is that at no time is the narrow tissue containing tip portion of the capsule subjected to tensile or compressive forces as has been the case in the past. Thus, while virtually eliminating the changes of damaging the tissue sample involved, or the possibility of accidental bodily injury as is common with conventional capsule slitting apparatus and methods, it is clear that the apparatus of the present invention provides an extremely simple and effective means for slitting electron microscopy tissue embedding capsules. It may also be noted that the blade edges are arranged to clear the tip portion of the push rod but to penetrate capsule to the depth of the capsule casing so as to slit the casing on both sides but to minimize the opportunity for damage to the embedded tissue.

What is claimed is:

1. In an apparatus for slitting the outer casing of an electron microscopy tissue capsule of the type having a tissue particle embedded in a plastic block having cylindrical shaped body and frusto-conical shaped end portions with the block being encased in a casing of corresponding shape and with one end of said body portion exposed, comprising, in combination:
  - a. a base plate adapted to rest on a work surface;
  - b. a guide member rigidly supported on and above said base plate, said guide member comprising a block having a horizontal and centrally positioned open ended cylindrical bore extending within and throughout the length thereof and having an aperture formed in the top and adjacent a forward end of said block and communicating with said bore, said aperture being shaped to accept placement of an electron microscopy tissue capsule therethrough to rest in said bore in a loose slidable relation therewith;
  - c. an elongated push rod member residing and slideable in said bore and having a tip portion movable from a first position rearwardly of said aperture to a second forward position adjacent a forward end of said bore, said tip portion being shaped to engage at said first position the said exposed cylindrical shaped capsule block end portion and to push the capsule forwardly to said second position;
  - d. a plurality of blades having cutting edges, said blades being fixedly positioned in said guide member below said aperture and adjacent said bore and with said edges being positioned clear of the path of movement of said tip portion but within said bore sufficient to engage and slit the casing wall of said capsule when said capsule block end portion is forced by said tip portion from said first to said second position; and
  - e. an operator means mounted on said base plate for operating said push rod member, said operator means including resilient spring means mounted to constantly urge said push rod rearwardly and said

tip portion towards said first position and including a rotatable camming member having an operator handle adapted when rotated in one direction to force said push rod member forwardly and said tip portion to said second position to effect said slitting and when rotated in the opposite direction to allow said spring means to move said tip portion to said first position preparatory to receiving another capsule for slitting.

2. An apparatus as claimed in claim 1 wherein said operator means includes a roller member mounted on a rearward end of said push rod member, said camming member includes a camming track engageable with said roller member and said resilient spring means is effective to maintain said roller member and camming track in constant engagement.
